GREASE GUN

Clyde G. Butler, Cincinnati, Ohio, assignor to
The Cincinnati Ball Crank Company, Cincinnati,
Ohio, a corporation of Ohio

Application February 20, 1933. Serial No. 657,563

20 Claims. (Cl. 221—47.4)

This invention relates to a lubricating device of the character known to the trade as a hand type pressure grease gun.

Conventionally, guns of this type combine a 5 grease supply chamber and a grease ejecting chamber having a discharge end for interchangeably connecting to a so-called "lance" extension, or a flexible conduit, which coupling members extend the reach of the gun for application to the 10 respective fittings projecting from the part of the structure to be lubricated.

In many old type hand guns of this class, the grease discharge chamber is either parallel to or angularly disposed in relation to the casing constituting the grease supply chamber which makes 15 a unit difficult to hold upon a fitting during manual operation. In other old guns of this general type, it is impossible to easily apply the nozzle directly to a fitting or to hold it to a fitting securely while ejecting a charge of grease 20 under high pressure.

In addition to these disadvantages, it is a common fault of the ordinary commercial hand gun that the difficulty of holding the gun properly to 25 the fitting is increased from the fact that physical force is required to eject a charge and, that the gun structure is so organized that the application of that hand force is exerted in a general direction away from or laterally relative to 30 the fitting, thus tending to displace the gun in relation to the fitting whenever it is operated.

It is common experience that hand guns of this type requiring relative movement of the casing body and the actuating lever in a shear-like manner, which produces a wabbling, rendering it difficult to hold the gun steady when applied to the fitting or in permanent contact with the fitting.

This invention is intended to provide a practical solution to these and other familiar problems inherent in the use of hand operated grease guns now in common usage.

This concept, in its larger aspect, comprises the formation of a casing resembling a gun barrel, something that can be, as it were, aimed at the target or fitting and which is so organized as to be capable of being directly supported thereon, so that the body pressure, plus the manual force of operating the ejecting mechanism, shall exert a component force tending to increase the contact of the nozzle with the fitting and to steady the gun when in operation. To this end I provide a longitudinal, preferably separable or two-part casing, the members of which 55 are coupled together, both providing a grease

supply or low pressure chamber at one end and a self-contained high pressure grease chamber and ejecting mechanism at the other end, the forward end being provided with a fixed or rigid nozzle for direct contact with a fitting and the 60 ejecting mechanism being operated by a lever projecting from a medial portion of the casing and movable in the general direction of the flow of grease to eject the charge into the fitting. From this disclosure it will be obvious that all 65 the factors of body pressure and operating force are directed to and compounded upon the fitting to which the gun structure is applied.

One of the numerous advantages of this concept is, that it permits of a wide choice of casing design, depending on the artistic resources or the individual taste of the maker, and the original design characteristic of the casing herein disclosed forms the subject matter of a design application filed concurrently herewith. 75

Preferably, I employ a high pressure grease chamber embodying a longitudinally reciprocating ejecting piston with the operating mechanism disposed interiorly of the casing. This arrangement permits of the placing of a fulcrum for an 80 actuating lever within a medial portion of the casing in more or less approximate alignment between the butt end of the gun and the rigid nozzle and to provide that this lever shall be movable in the same general direction as the movement 85 of the piston toward the discharge end of the gun. The law of this structure and organization is particularly useful in that it enables the coordination of the different body members which come into play when a fitting is to be lubricated 90 with this sort of gun. That is to say, the gun may be held to the shoulder as an ordinary shot gun so as to bring the body pressure on the gun directly in the line of the fitting, while at the same time the operating hand pushes the ejecting 95 lever toward instead of away from the fitting.

Moreover, this improved gun has the distinct advantage that, due to the direction of operation of the lever and the fact that the grease discharging pressure is exerted in line with the application pressure to hold the gun on the fitting, the gun can be operated with one hand, the shoulder or hip being against the rear end of the gun for locating it on the fitting. Therefore, the other hand is free for other uses, such as operating a shaker bar to loosen the springs or parts being lubricated. 100 105

In addition to this, the lever is arranged relative to the gun barrel so that when retracted, it lies fairly close to the barrel and is held in this 110

position because of the grease feeding pressure which is then effective against the head end of the discharge piston.

Other features of the invention will be more fully set forth in a description of the accompanying drawings, in which:

Figure 1 is a longitudinal sectional view of the improved hand operated grease gun.

Figure 2 is an enlarged view of the forward 10 head or pressure unit of the gun, showing the operating lever and piston moved forwardly in a grease ejecting stroke.

Figure 3 is a sectional view taken on line 3-3, Figure 2, detailing the connection of the operating lever to the grease discharge piston and the 15 pivotal connection of this lever to the casing of the gun.

Figure 4 is a sectional view taken on line 4-4, Figure 2, detailing the grease discharge cylinder 20 and showing the inlets thereto.

Referring to the details of structure shown in the drawing, the gun in general comprises a barrel forming a grease supply or relatively low pressure chamber 5, a head including a supporting and grease flow casing 6 carrying a grease discharge or relatively high pressure cylinder 7 and piston 8 and a discharge tube or lance 9 for butting engagement with the conventional butt type fitting (not shown). The pressure head unit 25 and the barrel have screw-threaded connection, the barrel being screwed into the head and the general relation of these major parts being coaxial or aligned so that the general casing arrangement is long and slim for convenient manipulation into those close quarters sometimes found in obtaining access to lubrication fittings of automobiles. The pressure head or casing is tapered to the forward end for further convenience in application to fittings.

40 Within the supply chamber, a grease forcing mechanism is provided. In this particular case, according to the illustration, this grease supply or forcing means consists of a follower plate or piston 10 fitting within the barrel and operating 45 on an axially disposed retraction rod 11, the rod including a stop 12 on its forward end provided by screwing a nut thereon and includes a brace or stock 13 on its rearwardly exteriorly extended end. The stock in addition to the provision of a 50 pad for the application of body pressure longitudinally of the gun, is formed for convenient manipulation, that is, provides an opening 14 so that the fingers may be slipped through and a 55 convenient grip obtained for retraction of the rod and piston or follower plate during loading or filling operations.

The rear end of the barrel is closed by means of a cylinder head or cap 15 screwed thereon, providing a slide bearing for the retraction rod. 60 A packing gland 16 is screwed into the cap providing a sealed, sliding fit for the rod. The stock or brace is rigidly fixed on the outer end of the rod and includes a screw-threaded forward shank 17 adapted to be screwed into a screw-threaded 65 bore in the packing gland for the purpose of fastening the retraction rod in plunged or forwardly moved position after the gun has been loaded.

70 In this particular case, air, as an actuating means, is supplied under pressure in back of the follower plate for forcing the same against the body of grease, the air being introduced through a conventional valved nipple or stem 18 screwed into the rear head. The head also includes a 75 relief valve 19 for exhausting the air from the

barrel when it is desired to retract the piston. A spacer sleeve 20 is mounted on the rod to limit rearward retractive movement of the piston to prevent the operator from drawing the follower plate against the rear head.

80 The follower plate assembly is as follows: A pair of reversely facing cup gaskets 21 are butted together. A cup-shaped spring element 22 including spring flanges for holding the flanges of the gaskets against the barrel inner surface are provided, one in each gasket. Washers 23 lie against the respective sides of this assembly and the assembly is held together by means of hub elements screwed together, including flanges abutting the respective sides of the aforesaid assembly.

85 More specifically, the hub elements include an intermediate sleeve 24 screw-threaded on both ends externally and fitted on the retraction rod, a flanged nut 25 screwed on one end of the intermediate element and lying against one washer and a sleeve 26 screwed on the opposite end, lying against the other washer and having a sliding fit on the retraction rod.

90 More specifically, the hub elements include an intermediate sleeve 24 screw-threaded on both ends externally and fitted on the retraction rod, a flanged nut 25 screwed on one end of the intermediate element and lying against one washer and a sleeve 26 screwed on the opposite end, lying against the other washer and having a sliding fit on the retraction rod.

95 Two devices are provided for preventing leak- 100 age of grease past the follower plate along the surface of the retraction rod. A spring-urged, cone-shaped packing element 27 is contained within an internal counterbore of the intermediate element and engages against a cone-shaped 105 packing 28 lying against the inner end of a counterbore 29 in the sleeve element for forcing this cone-shaped packing upon the rod. The other device is contained within the sleeve element 26 within a counterbore 30 in its outer end and consists of a flanged packing ring 31 held against the inner end of the counterbore and about the rod by means of a gland 32 screwed into the counterbore and overlying the ring.

110 The retraction rod is conveniently withdrawn 115 by the operator by grasping the manipulating and pressure applying element 13 and unscrewing the same from its rear connection. The forward head is first unscrewed and thereupon the forward end of the barrel is plunged in the grease 120 bulk and the retraction rod drawn back, drawing the follower plate against the spacer sleeve and sucking the barrel full of grease. Thereafter the rod 11 is shoved forwardly, screwed back into position, the head is screwed onto the barrel, and 125 a supply of air under pressure is introduced into the barrel in back of the follower plate, the gun then being operative for supplying a constant flow of grease into the pressure head.

130 The head of the gun is generally hollow. Its casing 6 is formed to provide a grease flow passageway 33 at one side of the axis thereof but within the region defined by the circle or circumference of the barrel. The conduit portion of the casing thus provided being disposed to one 135 side, provides a clearance space 34 for mounting of the operating lever for the grease discharge piston 8 on the casing and attachment to the piston. The piston 8 is mounted across this clearance space and has a bearing in the head at both 140 ends. The cylinder 7 is screwed into the head from the forward end and supports the forward end of the piston.

145 The axial relation of the grease forcing piston 8 and cylinder relative to the barrel is slightly offset for manufacturing purposes. This disalignment is not to any great degree and the high pressure piston and cylinder being contained within the area bounded by an extended circumference of the barrel.

150

- For the purpose of operating the grease discharge piston, a lever 35 is provided extending laterally from the head. For the purpose of mounting this lever, spaced ribs 36 extend across the clearance space 34, one at each side of the high pressure piston, and the lever is pivoted upon a pin 37 fixed across the space between the ribs and between the piston and the supply passageway.
- 10 The forward or attached end of the lever is bifurcated, thereby straddling the piston. Adjacent the pivot connection of the lever the piston is annularly grooved as at 38. This groove may be provided as shown by making the piston in two pieces, 39, 40, the rear section including a counterturned shank 41 extending into the head rear end of the forward section and pinned thereto, the respective heads being spaced to provide the annular groove.
- 15 20 The lever is flexibly connected to the piston through this groove. For this purpose a pair of trunnion blocks 42, one at each side of the piston and lying within the groove at the respective sides are rotatably mounted on the respective arms 43 of the bifurcated lever on pins fixed in the arms.
- 25 The lever is of sufficient length to give extremely great leverage and since the lever pivot point and connection to the piston are extremely close, the leverage produces an extremely effective discharge pressure. The ejecting movement of the piston is forwardly since the pivot is above the piston. This is distinctly advantageous in that the high pressure grease ejecting movement of the piston produced by moving the lever forwardly compounds the force applied against the butt type fitting through the application of body pressure on the shoulder brace or butt at the rear end of the gun.
- 30 35 40 The lever for operating the piston is curved rearwardly so as to lie relatively close to the gun barrel when retracted and is normally held in this position automatically by the supply pressure on the grease exerted against the journal end of the piston.
- 45 The grease discharge cylinder, as stated before, is screwed into the forward end of the high pressure head. Its extreme inner end is counterturned as at 44 to fit within a small bore portion of the head. A second counterturned portion is provided which is screw-threaded into a screw-threaded bore portion 45, the shoulder 46 between the counterturned portions engaging against a packing ring 47 lying against the adjacent shoulder of the head. This cylinder element is screwed into position against a shoulder 48 constituted by a nut portion 49 exteriorly of the head.
- 50 55 60 The supply passageway 33 extending to the forward end of the head turns inwardly at the outer end of the head and communicates with an annular groove 50 in the cylinder element, radial passageways or ports 51 connecting the annular groove with the cylinder bore. The piston in fully retracted position is drawn past these ports so that the grease is free to enter the cylinder in front of the piston after each retraction stroke. The discharge tube or lance 9 is shown as of the rigid type consisting of a tube having a butt head 52 concave on its outer end for a sealing fit with the tip of a lubricating fitting of the butt type. This tube is secured to the gun assembly specifically to the cylinder element by means of a coupling element 53. The coupling element is screwed into an internal bore of the
- cylinder and includes a nut portion for manipulation thereof. Its inner end engages a packing ring 54 and the packing ring 54 lies against a valve seating ring or washer 55 lying against an internal shoulder of the cylinder element between the coupling receiving bore and the main cylinder bore.
- 65 70 75 80 A ball valve 56 is provided mounted in a chamber of the coupling and urged by means of a coil spring 57 under compression within a counterbore, against a tapered seat formed on the outer side of the valve seating washer 55. The ball extends through the washer a sufficient amount to be unseated by the piston at each forward or discharge stroke by direct contact, the piston being limited in forward movement by engagement with the washer, the bore of which is of smaller diameter than the bore of the cylinder. The discharge tube or lance includes a rear head 58 which is screwed over an extended nipple of the coupling element and which includes an annular shoulder 59 fitting into a counterbored portion of the coupling element against a cup-shaped packing 60 spring-urged outwardly against the annular shoulder.
- 85 90 95 100 The discharge tube or lance may be replaced by flexible hose and a coupling on the end of the hose for locking attachment to pin type fittings. When the rigid or fixed lance or discharge tube is engaged against the fitting, the pressures applied to the gun by the operator are jointly directed in substantial alignment throughout the gun and are compounded for obtaining a positive sealing engagement in direct line and under considerable application pressure. The forces applied in the manual operation of the gun are all within the small diameter of the gun since all parts through which pressure is applied lie within the circle of the gun. This eliminates any tendency to tilt or cant the gun under the ejecting forces.
- 105 110 115 Having described my invention, I claim:
1. A grease gun, having a longitudinally continuous barrel-like grease casing terminating in a rigid fitting engaging nozzle, said casing being of relatively large diameter at the butt end providing a grease supply chamber, and of relatively reduced diameter at the nozzle end providing a grease discharge chamber supplied with grease from the supply chamber, said supply and discharge chambers being disposed in longitudinal alignment, an independent grease ejecting mechanism entirely contained within the grease discharge chamber casing, and a member on the casing in the rear of the nozzle for manually actuating said mechanism independently of gun application to the fitting.
- 120 125 130 135 140 145 150 2. A grease gun, having a longitudinally continuous barrel-like grease casing rigid from end to end, said casing being of relatively large diameter at the butt end providing a low pressure grease chamber, and of relatively reduced diameter at the muzzle end providing an elongated high pressure grease chamber supplied with grease from the low pressure chamber, said supply and discharge chambers being disposed in longitudinal alignment an independent grease ejecting mechanism in the high pressure chamber, and a lever having a handle portion projecting laterally from an intermediate portion of the casing for manually actuating said mechanism, the projecting handle portion of said actuating lever being movable in the general direction of the movement of the grease to eject a charge into a fitting.
3. A grease gun having a unitary casing, one

portion of which is of relatively large diameter providing a low pressure grease chamber, the other portion of which is of relatively reduced diameter forming an axially communicating continuation of the larger portion of the casing providing a high pressure grease chamber forming a continuation of and communicating with the low pressure chamber, means entirely self-contained within the high pressure chamber for 5 ejecting a charge of grease, and an actuating lever fulcrumed in the casing and having a handle portion projecting laterally from an intermediate portion of the casing manually operable for ejecting a charge of grease under high pressure, said 10 lever connected with the high pressure means intermediate of the fulcrum and handle portions of the lever.

4. A grease gun, comprising, a unitary casing having a large portion and a reduced portion 20 forming an axially communicating continuation thereof, a reciprocating piston and operating mechanism self-contained within the smaller portion of the casing constituting a high pressure ejecting means, and a manually operable member projecting laterally from an intermediate portion of the casing for operating the ejecting mechanism when said member is moved in the general direction toward the muzzle end of the gun.

30 5. A grease gun, having a unitary casing rigid from end to end providing a butt end and a rigid fitting engaging nozzle, one portion of which casing is of large diameter and the other portion of which is of relatively small diameter, said casing 35 sections providing end abutting and communicating low pressure and high pressure grease chambers, the axis of the high pressure chamber being slightly offset in relation to the axis of the low pressure chamber but disposed within a medial portion of the circumference of the larger or low pressure chamber, means for constantly exerting pressure on the grease in the low pressure chamber, ejecting means self-contained within the high pressure chamber, and an independent manually operating lever for said ejecting 40 means intermediate of the length of the casing for ejecting a shot of grease under high pressure.

6. A grease gun, comprising, a barrel-like casing having a butt-positioning member at one end and a fixed fitting engagement ejection nozzle at the other end, said casing being longitudinally subdivided into an organized low pressure grease chamber and an organized and a communicating high pressure grease chamber, a self-contained mechanically operated grease ejector therein, and a manually operated actuating member projecting through an intermediate portion of the casing operatively connected with the high pressure ejection mechanism.

7. A grease gun, comprising, a barrel-like casing having a butt-positioning member at one end and a fixed fitting engagement ejection nozzle 65 at the other end, said casing being longitudinally subdivided into an organized low pressure grease chamber and an organized and communicating high pressure grease chamber, a self-contained mechanically operated grease ejector therein, a manually operated actuating member projecting 70 through an intermediate portion of the casing operatively connected with the high pressure ejection mechanism, and means rendering said mechanism active to discharge a shot of grease 75 when said manual member is pushed in the gen-

eral direction of the fitting and inactive on the return stroke.

8. A lubricant supply gun, comprising, a barrel having a stock at its rear end for application of pressure longitudinally of the barrel and a butt type nozzle at its forward end adapted to engage a butt type fitting, said barrel including a lubricant forcing means therein urging the lubricant to the forward end of the barrel, a high pressure cylinder at the forward end of the gun contained within the circumference of the barrel and in alignment with the nozzle, said cylinder receiving the lubricant, a high pressure piston operable in said cylinder, and a manually operated piston reciprocating device located exteriorly of the gun. 80

9. A grease gun, comprising, a barrel including a pressure applying element at its rear end and a butt type nozzle at its forward end rigidly fixed to the barrel, follower plate mechanism for urging the grease forwardly in the barrel, a high pressure cylinder receiving the grease and disposed within the circumference of the barrel and in alignment therewith, and a manually operable lever extended laterally from the cylinder, said lever mounted relative to the cylinder and connected to the piston whereby the piston is operated in its forward or discharge stroke by forward movement of the lever. 95

10. A grease gun, comprising, a barrel including a pressure applying means at its rear end 105 and a rigidly fixed butt type nozzle at its forward end, a high pressure cylinder disposed within the circumference of the barrel and substantially coaxial therewith, means for forcing the grease forwardly in the barrel into the cylinder, a high pressure piston in said cylinder, a lever for actuating said piston pivoted to the cylinder approximately on the axial line of the barrel and having operative connection to the piston, the manipulating end of said lever extending laterally away from the barrel and the connection to the piston being disposed whereby forward strokes of the lever cause forward discharge strokes of the piston. 110

11. In a hand operated grease gun, an elongated casing structure including a discharge chamber and a grease supply chamber in communication with the discharge chamber, a butt at the rear of the casing, a nozzle at the forward end of the casing longitudinal of and in line with 125 the casing, a discharge piston in the discharge chamber operating directly toward the nozzle, and a lever laterally extended exteriorly of the casing for operating said piston. 120

12. A grease gun comprising two sectional casings 130 separably united longitudinally, said casings constituting a grease supply chamber formed with a body positioning member and a high pressure grease chamber formed with a rigid fitting engaging ejection nozzle, adapting the unitary 135 casing structure to be supported directly upon a fitting, a grease ejecting mechanism self-contained within the high pressure chamber, and an external laterally extended actuating member in rear of the fixed nozzle movable in relation to 140 the casing for ejecting a charge of grease.

13. A grease gun, comprising, a longitudinal gun-barrel-like casing having a rigid fitting engaging discharge nozzle adapted to be supported directly on a fitting at its forward end and a butt 145 positioning member at its rear end, said casing comprising a supply chamber communicating with a high pressure chamber, a grease ejecting mechanism interior of the high pressure chamber in rear of the fixed nozzle and an exterior 150

ally and laterally extended actuator movable in relation to the casing in the general direction of the nozzle for ejecting a charge of grease.

14. A hand-operated grease gun, comprising, a supply barrel, an extended hollow head for said barrel including a passageway in communication with the barrel extending forwardly through the head at one side of the axis of said barrel but within the region bounded by the circumference thereof, a pressure cylinder, a piston in said cylinder, said cylinder and piston mounted in the head and having their axes parallel with the axis of the barrel and within the region defined by the circumference thereof, said cylinder including an annular groove in its outer surface in communication with the supply passageway of the head, and radial ports connecting the annular groove with the bore of the cylinder, a valve mounted in the cylinder opening to discharge of grease, and a lever pivotally mounted in the casing between the axis of the piston and the supply passageway and extended laterally from the head, said lever having a flexible operative connection to the piston.

15. A hand-operated grease gun, comprising, a supply barrel, an extended hollow head for said barrel including a passageway in communication with the barrel extending forwardly through the head at one side of the axis of said barrel but within the region bounded by the circumference thereof, a pressure cylinder receiving grease from said passageway, a piston in said cylinder, said cylinder and piston mounted in the head and having their axes parallel with the axis of the barrel and within the region defined by the circumference thereof, a valve mounted in the cylinder opening to discharge of grease, and a lever pivotally mounted in the casing between the axis of the piston and the supply passageway and extended laterally from the head, said lever having a flexible operative connection to the piston.

16. A hand-operated grease gun, comprising, a supply barrel, an extended hollow head for said barrel including a passageway in communication with the barrel extending forwardly through the head, a pressure cylinder, a piston in said cylinder, said cylinder receiving grease from said passageway when the piston is drawn back, said cylinder and piston mounted in the head and having their axes parallel with the axis of the barrel within the region defined by the circumference thereof, and a rearwardly curved lever pivotally mounted in the casing between the axis of the piston and the supply passageway and extended laterally from the head, said lever having a flexible operative connection to the piston.

17. In a hand operated grease gun, a casing structure providing a grease supply chamber and a grease discharge chamber in communication with the supply chamber, a brace at the rear end

of the casing structure for applying body pressure longitudinally of the casing structure, a rigid fitting engaging discharge nozzle extended from the forward end of the casing structure and adapted for engagement with a fitting, a grease discharge piston and cylinder in the discharge chamber disposed lengthwise of the casing structure, and a lever for operating said piston, said lever extending exteriorly of the casing structure and adapted to be swung lengthwise of the casing structure.

18. A hand operated grease gun, comprising, a grease supply barrel including a low pressure grease forcing means therein, a rear closure on said barrel, a head on said barrel, said head including a grease flow passageway extending from the supply barrel to the forward end of the head, a discharge nozzle extended rigidly from the head and adapted to supply grease to a fitting, a discharge cylinder supplied from said grease flow passageway, a discharge piston in said cylinder adapted to eject grease through said nozzle under relatively high pressure, said nozzle, discharge cylinder, and piston disposed longitudinally of the barrel structure and within the circumferential lines thereof, a lever pivoted in the head and having a flexible connection to the piston, said lever extending laterally from the head and adapted to be swung toward and from the nozzle, and a brace at the rear end of the barrel for applying body pressure longitudinally of the gun.

19. In a hand operated grease gun, an elongated casing structure including a discharge chamber, a butt at the rear of the casing, a nipple engaging nozzle at the forward end of the casing longitudinally of and in line with the casing, a discharge piston in the discharge chamber operating directly toward the nozzle, and a lever operatively connected to said discharge piston and extended laterally from the casing and adapted to be swung lengthwise of the casing and generally toward the nozzle for a discharge stroke of the piston.

20. A manually operable grease gun having at its forward end a rigid nipple engaging nozzle adapted to engage a fitting, a stock at its rear end in substantial alignment with said nozzle so that pressure applied upon said stock tends to engage the nozzle with the fitting, a high pressure grease ejecting mechanism for feeding grease through said nozzle, said gun having a supply passageway extended to said high pressure ejecting mechanism, and a lever operatively connected to said high pressure grease ejecting mechanism and mounted in position in advance of said stock, said lever so positioned that the operating force exerted upon it during the working portion of its stroke is applied substantially parallel to the line between the butt and nozzle.

CLYDE G. BUTLER.
